SAVING BANK

Frank H. Kemper, Chicago, Ill.

Application June 27, 1958, Serial No. 51,571

Term of patent 14 years

(Cl. D34—5)

Fig. 1 is a perspective view of a saving bank showing my new design;

Fig. 2 is a top plan view of the same; and

Fig. 3 is a bottom plan view of the same.

The broken line representation in Fig. 1 designates a slot which is shown for illustrative purposes.

I claim:

An ornamental design for a saving bank, substantially as shown and described.
